(57) **CLAIM**

I claim the ornamental design for the locking peg board back, as shown and described.

DESCRIPTION

FIG. 1 is a perspective view of the locking peg board back; FIG. 2 is another perspective view of the locking peg board back;

FIG. 3 is a back perspective view of the locking peg board back;

FIG. 4 is a front view of the locking peg board back;

FIG. 5 is a back view of the locking peg board back;

FIG. 6 is a side view of the locking peg board back;

FIG. 7 is another side view of the locking peg board back showing the side opposite that shown in FIG. 6;

FIG. 8 is a top view of the locking peg board back;

FIG. 9 is a bottom view of the locking peg board back; and FIG. 10 is an exploded front perspective view of the locking peg board back;

FIG. 11 is another exploded front perspective view of the locking peg board back;

FIG. 12 is an exploded back perspective view of the locking peg board back;

FIG. 13 is another exploded back perspective view of the locking peg board back;

FIG. 14 is an exploded side perspective view of the locking peg board back; and,

FIG. 15 is another exploded side perspective view of the locking peg board back.

The broken lines represent portions of the structure that forms no part of the claim.
